UNITED STATES PATENT OFFICE.

EMMA A. SYLVESTER, OF BOSTON, MASSACHUSETTS.

DESIGN FOR A PURSE.

SPECIFICATION forming part of Design No. 36,180, dated December 30, 1902.

Application filed November 24, 1902. Serial No. 132,705. Term of patent 3½ years.

To all whom it may concern:

Be it known that I, EMMA A. SYLVESTER, a citizen of the United States, and a resident of Boston, in the county of Suffolk and State of

Massachusetts, have invented and produced a new, original, and ornamental Design for Purses, of which the following is a specification, reference being had to the accompanying drawings, forming part thereof.

Figure 1 is a side elevation of a purse, showing my new design; and Fig. 2 is a bottom plan view of the same.

As shown in the drawings, the leading or material feature of my design consists in a curved frame A, having substantially parallel ends A', and a purse or receptacle having outwardly-flaring edges B B, terminating as a convex fluted or corrugated bottom C, and

having fan-shaped sides upon which are a series of convex surfaces D D D gradually tapering in width from the bottom upward, and having intermediate grooves or depressions E E E, as shown in the drawings.

Having described my invention, what I claim as new, and desire to secure by Letters Patent and claim, is—

The ornamental design for a purse, as herein shown and described.

In testimony whereof I have signed my name to this specification in presence of two witnesses.

EMMA A. SYLVESTER.
